UNITED STATES PATENT OFFICE.

ALBERT C. SCHLIEPER AND HENRY G. STEINBOCK, OF ALLEGHENY,
PENNSYLVANIA.

STUD.

SPECIFICATION forming part of Letters Patent No. 722,540, dated March 10, 1903.

Application filed September 11, 1902, Serial No. 122,926. (No model.)

To all whom it may concern:

Be it known that we, ALBERT C. SCHLIEPER and HENRY G. STEINBOCK, citizens of the United States of America, residing at Allegheny, in the county of Allegheny and State of Pennsylvania, have invented certain new and useful Improvements in Studs, of which the following is a specification, reference being had therein to the accompanying drawings.

This invention relates to certain new and useful improvements in buttons, and relates more specifically to that form of button known as a "stud;" and the main object of the invention is to construct a stud which may be inserted in one ply of material and held securely therein before the second ply of material is placed in position on the stud and secured by means of a head.

As stated above, the invention particularly relates to what are known as "stud;" and it consists in a stud having two shanks, with an intermediate disk or head, each shank having a detachable head, whereby one shank may be inserted through one ply of material, the head placed thereon, and the button thus held in position, after which the other ply of material may be placed on the other shank and the head of the latter placed thereon to retain the second ply of material.

In describing the invention in detail reference is had to the accompanying drawings, forming a part of this specification, and wherein like numerals of reference indicate like parts throughout the several views, in which—

Figure 1 is a detail perspective view showing a portion of a shirt-front and illustrating the application of our improved stud. Fig. 2 is a detail side elevation of the several elements disconnected. Fig. 3 is a side elevation of the stud in position on the shirt-front, a portion of the latter being in section. Fig. 4 is a detail elevation of the several elements disconnected, showing a modified form of construction, the disk or central head and shanks being in section. Fig. 5 is a longitudinal section through one of the heads, showing the form of fastening. Fig. 6 is a central sectional view through the central member in the modified form of construction.

As heretofore stated, the main object of our

invention is to provide a stud having a detachable head on each end. To this end we provide a central disk or head 1, extending from the center of which on each side are the integral elongated shanks 2 and 3, said shanks being of the same diameter. These shanks are each adapted to receive the detachable heads 4 and 5, which may be of any approved form and may be secured on the shanks in any desired manner, a convenient one being by means of the form of fastening 5 shown in Fig. 5, which consists of spring-catches which have pins projecting through the periphery of the head at opposite sides thereof, these pins being adapted to be forced within the casing of the head, whereby the catches 6 may be disengaged from the groove 7, provided therefor in the shanks 2 and 3. This form of stud is illustrated in Figs. 1 and 3, in Fig. 1 the shank 2 being shown inserted through the under ply 8 of the shirt-front with the head 4 placed in position thereon. When in this position, it will be observed that the stud is secured in position by the head 4 and the disk or head 1, between which two elements the ply 8 is held. The ply 9 may then be placed upon the shank 3 and secured by means of the head 5. It will thus be seen that the stud may be placed in position and securely retained in one ply of the material in order that the shirt may be fastened after being put on.

In Fig. 4 we show a modified form of construction, the shanks 2' and 3' of the central head or disk 1' having a recess 4' in their ends to receive the pins 5', carried by the detachable heads 6' 7'. These heads are of an approved form, having pins at the opposite sides of the periphery which are compressible, so as to permit the disengagement of the pins 5' from the shanks, which pins are carried by the catches 6. (Shown in Fig. 5.)

In Fig. 6 the head or disk 1^a, as shown, is constructed with a front shank 2^a of greater length than the rear shank 3^a. These shanks 2^a and 3^a are shown as provided with recesses 4', as in the construction shown in Fig. 4.

It will of course be evident that the detachable head may be of any desired style and form other than is shown, and in the construction of the invention it will be noted

that various changes may be made in the details without departing from the general spirit of the invention.

Having fully described our invention, what we claim as new, and desire to secure by Letters Patent, is—

1. A stud of the type set forth, comprising a disk formed on its opposite sides with outwardly-projecting shanks, adapted to project through the garment to be secured, and heads engaging the said shanks only at points adjacent their outer ends and engaging only the outer and inner faces of the garment respectively.
- 15 2. A stud comprising a disk, shanks formed integral with the opposite faces of the said disk, said shanks each being formed at points

adjacent their outer ends with an annular groove, and detachable heads arranged on the said shanks and engaging the grooves thereof, substantially as and for the purpose specified.

3. A stud comprising a disk, outwardly-projecting shanks formed integral with the opposite faces of the said disks, and detachable heads secured on and engaging the said shanks only at their outer ends.

In testimony whereof we affix our signatures in the presence of two witnesses.

ALBERT C. SCHLIEPER.
HENRY G. STEINBOCK.
